[57] **ABSTRACT**

The invention relates to a control system for a levitation bed in which the patient is supported on an air cushion composed of a plurality of air pockets forming a mattress and comprises an air duct for supplying air to the pockets, the flow of air being controlled by a damper or butterfly valve operated by an hydraulic cylinder energised by air from a static pressure transmitter which senses any change in pressure in the duct.

6 Claims, 5 Drawing Figures

LEVITATION BEDS

This invention relates to improvements in levitation or low loss air beds for medical purposes of the kind in which the patient is supported on an air cushion when suffering from severe burns. Earlier beds of this construction have been found to operate satisfactorily only as long as the patient does not move.

This earlier bed is an inflatable chamber with an outlet formed by a number of pockets which is self-adjusting in three planes. As each pocket inflates it is forced against its neighbour and it also meets the opposite pockets along the mid-line of the bed and along the mid-line of each leg. After the patient is put on the inflated bed the pressure is adjusted so that the pockets are depressed sufficiently by the downward thrust of the body to allow pressurised air to leak between the body and the top surface of the pockets. Those portions of the pockets beneath the body are subject to the same pressures on their inner and outer surfaces and thus fall away from the patient while those portions outside the body profile remain inflated.

According to the invention, a control system for an air support levitation bed to maintain a substantially constant air pressure in the pockets thereof forming a mattress comprises an air duct for supplying air to the pockets; a damper or valve in the duct to open and regulate the supply of air, so that the air may be regulated to oppose the weight of various patients such as children and adults, and means once this equilibrium has been established to maintain the equilibrium automatically, even when the air leak is varied due to the patient moving about; a pressure tapping or sensor to detect any variation in air pressure in the pockets; a pneumatic, electric or electro-pneumatic pressure regulating and compensating system, calibrated to the weights of patients, controlling the supply of compressed air to a pneumatic cylinder, the piston of which operates a linkage to hold the damper or valve in the required position to obtain the correct constant air pressure to support the weight of the patient, and to open the damper or valve when any drop in pressure occurs in the pockets of the bed due to the movement of the patient, and to return to the required holding pressure once movement of the patient has stopped.

The invention will be described with reference to the accompanying drawings:

FIG. 1 is an end elevation of a bed.

FIG. 2 is a part side elevation of same showing diagrammatically a control circuit therefor.

FIG. 3 is a similar view of a further circuit arrangement.

FIG. 4 is a similar view incorporating a safety circuit.

A levitation air bed A is formed with a plurality of open ended pockets a forming a mattress extending from both sides of the bed frame to meet on the longitudinal centre line of the bed. Air is supplied from a duct A¹ to an annular chamber formed as an envelope a¹ surrounding the pockets a. The air passes into the pockets a the outer ends of which are connected to the envelope. The air inflates the pockets a on each side of the bed and as each pocket is inflated it is forced against its neighbour and also meets the opposite pocket along the central longitudinal axis of the bed.

A control of the air supply is provided to compensate for excessive escape of air from the pockets and the subsequent loss of levitation pressure when the move-

ment of a patient on the bed upsets the equilibrium of air pressure in the pockets.

The air supply to the duct A¹ under a pressure of between 6 inches and 15 inches water gauge, is controlled by a damper or butterfly valve 1 actuated by a piston in a pneumatic cylinder 2 through a linkage 3. Compressed air at a reference pressure of 20 p.s.i. is fed direct to a receiver 4 and also indirectly to the receiver through a restrictor valve 6 and a gradual switch. Compressed air from the restrictor valve 6 is connected to a differential static pressure transmitter 5 which senses the change in air pressure in the duct through a small bore pipe 7 connected to a static tapping 8. The air support or levitation bed is supplied with sterile conditioned air from a remote air feed system. The air pressure at the bed is adjusted according to the weight of the patient. The correct air pressure for the weight of the patient is selected by a variable control valve 9 which allows the transmitter 5 to leak-off compressed air from the restrictor valve 6 which in turn, reduces the compressed air feed back to the receiver. The receiver 4 automatically adjusts the correct compressed air pressure to feed the cylinder 2 and this moves the damper 1 to the correct position to maintain a constant air pressure at the bed. Any drop in air pressure at the bed, due to the movement of the patient, will immediately be sensed by the static air pressure tapping 7 and conveyed to the transmitter 5 which leaks off more compressed air from the restrictor valve 6 which then reduces the compressed air pressure feed back to the receiver 4. The receiver 4 automatically reduces the compressed air feed to the cylinder 2 which in turn opens the damper 1 and allows more air to the bed, thus restoring the required levitating pressure.

In an alternative arrangement FIG. 3, a variable control feeds compressed air at a maximum pressure of 20 p.s.i. through a solenoid valve 10 to the cylinder 2. A single phase electrical supply is connected to terminals which in turn feed the solenoid valve 10. The neutral line is connected direct to the solenoid valve 10 and the line supply passes through a normally closed micro-switch 11 inside an air pressure switch 12 before being connected to the normally closed solenoid valve. The air pressure switch 12 is connected by a small bore pipe 13 to the static pressure tapping 8. A fall in pressure in the supply duct A¹ is sensed by the pressure switch through the tapping 8 which opens the micro-switch 11 to cut off the electrical supply to the solenoid valve 10 and opens the valve. This sequence allows compressed air to escape from the cylinder 2 which opens the damper 1 or valve.

The air support system of the bed is supplied with sterile conditioned air from a remote air plant. The air pressure at the bed is adjusted according to the weight of the patient and may vary from 6 inches to 15 inches water gauge. The correct air pressure for the patient's weight is selected with the variable control which allows the correct pressure of compressed air to be fed to the cylinder 2 which in turn, adjusts the damper 1 to the correct levitating position. The compensating air pressure switch 12 is pre-set to operate at an air pressure below the normal operating range required for levitating the patient. If the patient moves excessively, when in a state of levitation, then this allows more air to escape past the patient and hence the pressure in the bed is lowered and the patient begins to sink into the bed until the pressure in the bed reaches the fixed set-

ting of the air pressure switch. This immediately breaks the micro-switch 11 inside the pressure switch and opens the solenoid 10 releasing the compressed air in the cylinder 2 which in turn, opens the damper 1 to admit full air to the bed. This gives maximum pressure in the bed and automatically raises the patient to the original setting of the variable control. The pressure switch 12 will close the micro-switch 11 as the pressure in the bed increases past the fixed setting thus re-establishing a state of equilibrium.

In the arrangement shown in FIG. 4 a safety feature is incorporated to prevent the patient from falling to the bottom of the bed if the pneumatic compensating mechanism acts too slowly to withstand a sudden violent movement.

An electric pressure switch 15 and a solenoid valve 16 are provided, the pressure switch having an adjustable range and is set at a pressure below that required to levitate the patient. If the patient reacts violently and the pneumatic system does not compensate in time, then the electric pressure switch 15 immediately detects the drop in pressure and immediately energises the solenoid valve 10, which in turn, evacuates the damper control cylinder 2 and allows full air volume onto the bed. This reaction lifts the patient to the top 25 of the bed and allows the pneumatic system to take over the normal levitating pressure control function.

What we claim is:

1. In combination, a levitation bed of the type having a pressurized chamber the outlet of which is formed by a plurality of inflatable pockets arranged as a mattress for underlying a patient, means for supplying air under pressure to said chamber and pockets whereby the weight of a patient on the bed may cause escape of pressurized air to establish and maintain in equilibrium a supporting air cushion between the upper surfaces of the pockets and the body of the patient, means including valve means for controlling said supply air pressure,

and means responsive to a change of equilibrium air pressure at said cushion due for example to movement of the patient relative to the pockets for automatically compensatively varying the air pressure derived from 5 said supply for maintaining substantially constant equilibrium air pressure at said cushion and preventing the patient's body from dropping into contact with said pockets.

2. In the combination defined in claim 1, said means 10 for varying the supply air pressure comprising means for sensing a change in air pressure downstream of said valve means operatively connected to said valve means.

3. In the combination defined in claim 2, means providing a reference pressure, and means wherein said 15 reference pressure and the pressure derived from said sensing means are correlated and having an output connected to control said valve means.

4. The combination defined in claim 1, wherein said valve means comprises a valve element movable in a supply duct and connected to be operated by a fluid pressure motor, and means is provided for sensing the pressure in said supply duct downstream of said element, correlating it with a reference pressure and applying a resultant control pressure to said motor.

5. In the combination defined in claim 4, means for varying the reference pressure to vary said supply pressure for establishing equilibrium in said air cushion.

6. In the combination defined in claim 4, a solenoid 30 valve in the line for applying said resultant pressure to said motor and an energizing circuit for said solenoid valve containing a normally open pressure switch that closes in response to a decrease in said supply pressure sensed by said sensing means to directly operate said motor to open said valve means in the event of delayed 35 action of said means correlating the reference and sensed supply pressures.
